A. MAXWELL.
APPARATUS FOR TREATING ELATERITE.
APPLICATION FILED SEPT. 5, 1916.

Patented Mar. 12, 1918.

Archibald Maxwell

UNITED STATES PATENT OFFICE.

ARCHIBALD MAXWELL, OF SALT LAKE CITY, UTAH, ASSIGNOR TO U. S. ELATERITE PRODUCTS COMPANY, OF SALT LAKE CITY, UTAH, A CORPORATION.

APPARATUS FOR TREATING ELATERITE.

1,259,260.

Specification of Letters Patent. Patented Mar. 12, 1918.

Application filed September 5, 1916. Serial No. 118,582.

To all whom it may concern:

Be it known that I, ARCHIBALD MAXWELL, a citizen of the United States, residing at Salt Lake City, in the county of Salt Lake and State of Utah, have invented certain new and useful Improvements in Apparatus for Treating Elaterite, of which the following is a specification.

My invention relates to apparatuses for 10 treating elaterite, and has for its object to provide an apparatus by which elaterite may be rendered soluble and economically and rapidly dissolved for use as paint.

These objects I accomplish with the apparatus illustrated in the accompanying drawings in which similar letters and numerals of reference indicate like parts throughout the several figures and as described in the specification forming a part 20 of this application and pointed out in the appended claim.

In the drawings in which I have shown a substantial embodiment of my invention, Figure 1 is an elevation of one of the refining furnaces. Fig. 2 is an elevation of one of the detachable grates. Fig. 3 is a vertical section of one of the grate cylinders. Fig. 4 is a plan view of one of the grate holders and grates therein. Fig. 5 is a vertical section of the dissolving tank and agitating means.

In the use of elaterite as a paint or coating for wood and iron one of the difficulties to overcome is to provide an economical and efficient solvent for the crude elaterite, and I have found that when the hydrogen, oxygen and sulfur that are found in the crude elaterite are partially burned out that the mass remaining is readily and may be 35 economically dissolved and carried in solution by turpentine and the lighter hydrocarbon liquids, such as gasolene and kerosene, and that the melting point is much higher than the elaterite. In the manufacture of a carbon coating or paint from elaterite it is highly desirable that the solvent be cheap, and the time required to mix the elaterite with the carrying liquid be limited; these objects I accomplish with the apparatus illustrated in the accompanying drawings. The furnace shown in Fig. 1 is one of the refining units used in the plant and by which the hydrogen, oxygen and sulfur are burned out; it consists of an elevated 55 metal cylinder A, having a detachable frusto-conically shaped cap or partial clo-

sure B. The said cylinder A is conveniently mounted on legs 1, of a length sufficient to allow time for the refined elaterite, which may be blazing when it leaves the said furnace, to burn itself out and to fall into the receiving tank C without blazing. A draft flue D is supported above the said cylinder and its cap B, to carry off the fumes of the burning elaterite and provide a draft for 60 the furnace. A door 2 is mounted over an opening in the wall of said cylinder for convenience in igniting a charge in the furnace and for watching the progress of the treatment. A detachable grate holder 3 is provided, having openings cut therein to receive the grates F, and having an outwardly turned flange 3 thereon; and is carried on and supported by the upper edge of said cylinder A. A detachable grate F is provided for and 70 carried in each of the openings cut in said grate holder E, and consists of a cylinder or band 4 having an outwardly turned flange 5 on its upper edge and an inwardly turned flange 6 on its lower edge and a basket 75 shaped wire mesh 7 forming its bottom. A receiving tank C is provided below the said grates to catch the refined elaterite as it falls from said grates. A number of said furnaces may be operated and attended by one 80 person and each of said furnaces, therefore, is herein termed a unit. To complete the treatment, a dissolving tank G is provided, having a perforated cover 8 thereon, and a steam or heat chest 9 forming the bottom 90 therein. An ingress and an egress pipe leading to and from said steam chest 9 is shown at 10 by which heat may be supplied under and to the contents of said tank. A power driven vertical shaft 11 is mounted in said 95 tank G, and perforated paddles 12 are secured on and rotated with said shaft to agitate the contents of said tank. The circles shown in the paddles 12 of Fig. 5 are the perforations in said paddles and the flow of 100 the matter through said circular holes is to aid in thoroughly mixing the contents of said tank G.

The operation of my apparatus is as follows:—

The crude elaterite as it comes from the mine in lumps from the size of marbles or pebbles to chunks weighing two or three pounds, is placed in the detachable grates F; and they in turn are placed in the openings in said grate holder E, which on account of the heat radiating from the said

cylinder A has been temporarily removed therefrom, and said holder is placed within said cylinder with the flange 3 resting on the upper edge of said cylinder. The cap B is then lowered or secured as a partial cover for the cylinder, and the elaterite is ignited by means of a lighted torch which may be applied through said door 2 or from below said cylinder as desired. As the flame of the lighted elaterite spreads over the surface the sulfur, hydrogen and oxygen will be consumed with a small per cent. of the elaterite. The greater portion of the elaterite will melt and drip through the grates in the form of drops and be caught in the receiving tank C. Some of said drops may be blazing when detached from the melting mass in the grate baskets, but the flame will burn itself out, usually, by the time the carbon particle

reaches the said tank C. The refined elaterite ²⁰ caught in the tank C will solidify when allowed to cool and is then crushed and ground into particles resembling sand.

I thus provide an economical and efficient apparatus for treating elaterite to form a ²⁵ carbon coating or paint and claim:—

An apparatus for treating elaterite consisting of a cylindrically shaped furnace; a frusto-conically shaped cover therefor; a grate holder supported in said furnace; basket shaped grates carried in said holder; and a receiving tank below said grates. ³⁰

In testimony whereof I have affixed my signature in presence of a witness.

ARCHIBALD MAXWELL.

Witness:

SAM RANEY.
